PORTER H. BURLIN, OF LIMESTONE, NEW YORK.

COUPLING DEVICE FOR OIL WELLS.

1,415,788.

Specification of Letters Patent.

Patented May 9, 1922.

Application filed May 25, 1921. Serial No. 472,431.

To all whom it may concern:

Be it known that I, PORTER H. BURLIN, a citizen of the United States of America, residing at Limestone, in the county of Cattaraugus and State of New York, have invented a Coupling Device for Oil Wells, of which the following is a full and complete specification.

In the construction of an oil well the tubing through which the oil is pumped extends from the surface of the ground into the well to a point above the bottom thereof with the pump-piston located in the lower portion of said tubing, and for the purpose 10 of supporting this tubing a casing or stock is provided above the ground. The present construction and arrangement of the coupling for supporting the tubing, as well as the connections for the lead line or pipe 15 conveying the oil to the storage tank and for the gland through which the operating rod passes, are such that they are liable to injury and serious damage from the operation 20 of the rod and the effect of intense heat in case of fire being communicated to the oil accumulated around the casing or stock from the leaky joints loosened by the operation of the aforesaid rod, often times resulting in the tubing being disconnected 25 from its supporting connection and dropped into the well. When the tubing drops it requires the tedious and expensive operation of fishing it out, and in some instances this operation is unsuccessful on account of the 30 fallen tubing becoming so badly jammed or bent that it cannot be withdrawn, in which event the well becomes useless. Owing to the liability of the tubing becoming disconnected from its support from the above mentioned causes it is customary to provide a 35 device, termed a "catcher" which operates to catch and hold the tubing from dropping into the well.

The primary object of my invention is to 40 provide a coupling device of particular construction which will effectually overcome the dangers and objections presented by the couplings and connections now employed with the casing or stock, whereby to not only 45 safely protect the tubing connection in case of fire but also reduce to a minimum the possibility of leakage and consequent loss of oil through loose joints.

A further object of my invention is to 50 provide a particular form of coupling device

which will be simple and compact in construction to take the place of the numerous couplings and connections heretofore employed and permit of a more convenient connection between the operating-rod and jack. 60

Other objects and advantages of my invention will hereinafter appear, and what I claim as new is more specifically set forth in the appended claims.

In the accompanying drawings:

Fig. 1 is a side elevation of the upper part of an oil well, including the casing or stock and connections ordinarily employed at the upper end of the well tubing.

Fig. 2 is a similar view, showing the application of my improved coupling device in connection with the casing or stock.

Fig. 3 is a side elevation, partly in section, to show the application of the coupling device to the casing.

Figs. 4 and 5 are enlarged detail views of the coupling device constructed in accordance with my invention.

Like numerals of reference indicate like parts in the several views of the drawings.

In constructing the upper part of an oil well to conduct the oil from the well tubing and provide for the passage of the operating rod carrying the pump-line it is customary to provide a casing or stock 10, provided with a head 11 in which is seated an annular flanged disk 12 held in place by a set-screw 13, and into this annular disk is fitted a flanged ring 14 supporting thereon a collar 15 from which the well tubing 21 is suspended, the said collar also carrying a nipple 16 to which is connected a T-coupling 17 for the connection of the lead line 18 at one side and an extension 19 at top for the gland 19^a through which works the operating-rod 20 connected to the pumping-jack (not shown). The arrangement just described, and illustrated in Fig. 1 of the drawings is common to an ordinary oil well.

In carrying out my invention to simplify the arrangement at the upper end of the casing or stock and eliminate the objections to the ordinary connections I provide a coupling device 25, the body portion of which is provided at its lower end with a substantial annular flange 26 providing a supporting shoulder from which depends an extension 25^a internally threaded at its lower end to receive the upper end of the well-tubing 21, said extension being cylindrical and of

the proper size to fit snugly within the flanged annular disk 12 seated and secured in the casing-head. A threaded pipe connection 27 projects from one side of the coupling 5 above the aforementioned flange or shoulder to receive the lead line or pipe 18, and the coupling is extended above this pipe connection, at 28, to receive a gland-nut 29 having the usual packing-ring 30 through which 10 the operating-rod 20 passes. As this coupling device is intended to firmly support the well-tubing and cooperate with the annular disk to accomplish this purpose it is preferably made of steel, and the depending lower 15 portion below the shoulder is of such length that its threads and those at the upper end of the well-tubing will be located within the casing below the head thereof, to be thereby protected from heat in case the plat- 20 form which is usually provided around the casing or stock should catch fire and burn; it being understood that the provision of the 25 said coupling device practically eliminates the possibility of leakage of oil as in the case of the connections usually employed, such as illustrated in Fig. 1.

The application of my improved coupling device will be readily understood by reference to the drawings, for it is constructed to 30 be used in connection with the ordinary casing, casing-head and flanged disk, and being fitted in the latter provides for connecting the lead line pipe directly above the casing, and locating the packing for the 35 operating-rod at the upper end of said coupling; whereby a compact arrangement is provided at the upper end of the well-tubing and the usual number of joints that are liable to become loose and leak are dispensed 40 with. The coupling device also provides for more conveniently locating the pumping-jack, as the usually high foundation for the same is not required in the present instance.

As will be obvious the use of my improved coupling device will result in a safe and 45 more economical operation of the oil well, inasmuch as leakage will be eliminated and a practically indestructible joint or connection provided for supporting the well-tubing so that it will not be liable to drop into the 50 well.

The size of the coupling device will of course depend upon the size of the well-tubing with which it is employed, and therefore it may be made in different sizes. Also, instead of providing internal threads for the pipe connections external threads may be used, but in case the depending portion which receives the well-tubing is externally threaded a plain external surface must be 60 provided immediately below the shoulder to receive the flanged annular disk on the casing-head.

Having described my invention, I claim:

A coupling device for oil wells in one 65 piece or a single casting comprising a body portion having an outwardly projecting flange at its lower end providing a shoulder, an integral tube-receiving portion extending from said shoulder throughout of approxi- 70 mately the same diameter as said body portion threaded to receive the upper end of the well tubing and having a plain external surface immediately below the shoulder, a pipe connection projecting from one side of the 75 body portion, and a threaded integral tubular extension on the body portion above the connection to receive a gland nut; said coupling device being adapted for use in connection with a casing-head and an annular 80 disk secured in the upper end of said casing-head and upon which said coupling device is seated, as herein shown and described.

PORTER H. BURLIN.
